YORK, A CORPORATION OF NEW YORK.

ELECTRIC HOT-AIR FURNACE.

Application filed September 24, 1923. Serial No. 664,464.

Our invention relates to a hot-air furnace, and is particularly designed for utilizing electricity as the source of energy for supplying heat.

5 The objects of the invention are to provide a hot-air furnace which is simple, economical and practical, and which utilizes to the maximum advantage all, or substantially all, of the heat units generated.

10 Generically, this invention comprises a draft cylinder in which a heating unit is enclosed. The heat is produced by a resistance element which is relatively small with respect to the cylinder, and to compensate 15 for the proportional difference, radiator plates are employed to efficaciously distribute the heat.

To the accomplishment of the recited objects and others subordinate thereto, the 20 preferred embodiment of our invention resides in the the construction and arrangement of parts hereinafter described, illustrated in the accompanying drawings, and embraced within the scope of the appended 25 claims.

In said drawings:—

Figure 1 is a vertical elevation, partly in section, of the furnace embodying our invention.

30 Figure 2 is a transverse section taken along lines 2-2 of Figure 1, and

Figures 3 and 4 are detail side elevations of one of the radiator plates, and the water manifold, respectively.

35 Figure 5 is a top plan view of Figure 4.

Figure 6 is an enlarged fragmentary elevation of one of the radiator plates, illustrating the manner of mounting the resistance element.

40 Figure 7 is a sectional view taken on line 7-7 of Figure 6.

Figure 8 is an enlarged fragmentary elevation, partly in section, of the uppermost supporting connection of the radiator plates.

45 Figure 9 is a sectional view taken on line 9-9 of Figure 8, and

Figure 10 is a transverse sectional view taken on line 10-10 of Figure 8.

50 Referring to the drawings, and at first more particularly to Figure 1, (5) represents a cylindrical casing constructed, preferably, of galvanized sheet iron, and suitably connected and reinforced adjacent the top,

at the bottom, and an intermediate point, by iron rings (6). The upper extremity of 55 the casing is merged into a truncated crown (7) having a substantially concave top (8) and suitable hot air outlets (9) leading to registers (not shown). At the bottom, the casing is equipped with a cold air inlet (10) 60 and a door (11) for convenience in filling the water pan (12).

One or more radiators, preferably in the form of substantially rectangular shaped plates (13), together with a similarly shaped 65 water manifold (14), provided with an inlet (15) and an outlet (16), are combined with suitable electric resistance bars (17) to produce the desired heat for the furnace. If certain contingencies require that all of the 70 radiators, including the manifold, should be equipped with electric resistance bars, this could be done with facility. However, actual experiments which we have conducted 75 show conclusively that for ordinary requirements, it is necessary to provide only the alternate plates and the manifold with the resistance bars, and this is the manner in which the disclosure is made in Figures 1 and 2 of the accompanying drawings. 80

As illustrated, the plates have lugs (18) at their inner opposite corners which are secured at the top to the bars of the heat deflector, or inverted dome, (19) by bolts (20), and at the bottom to the flange (21) of the 85 upright (22), transverse slots (22^a) being formed at the base of the lugs for receiving nuts (22^b). A separate upright (23) is employed to sustain the manifold (14). When in place, as exhibited in Figures 1 and 2, the plates (13) and manifold (14) are disposed in the upper portion of the casing, and radiate from their inner adjacent edges outwardly to a point near the inner wall of the casing, sufficient space being allowed between 90 the outer edges of the plates and the wall of the casing to accommodate a cylinder (24) of asbestos-lined tin, or similar heat insulator, as well as to provide for a dead air space (25). The concave top (8) of the 95 crown of the casing is also preferably filled with a heat insulator, as quartz sand (26).

In accordance with the present showing (see Figures 6 to 8 inclusive), each alternate plate (13) and the manifold (14) are cast 100 105 with a diagonal slot (27) medially within

the confines of which are mounted the resistance bars (17). Specifically, opposite ends of the bar are gripped by a clamp (28) which are in turn suspended by coil springs (29) to allow for expansion and contraction. 5 Screws (30) serve to fasten the springs (29) to a bridge (31) of fireproof insulation, as transite asbestos, secured transversely of the terminals of the slot by bolts (32). The 10 screws (30) also serve as a connection for the electric wires (33) and (34) which are insulated by an asbestos cover and led through conduit (35) to a mutual outlet box (36). Interconnections (37) between the 15 electric resistance bars (17) as required by delta connection, are led through the plain radiator plates and are supported on them by porcelain bushings (38).

The maximum heat pressure will 20 obviously be exerted at the top of the radiator plates, and it therefore becomes necessary to provide a construction which will protect the crown (7) against heat radiation. We accomplish this by means of the hereinbefore 25 mentioned heat deflector (19), which not only functions to connect the upper ends of the radiator plates, but, combined with the concavity (8) of the top of the crown, leads the hot air into the outlet pipes (9) 30 and reverses the direction of ascending heat towards the path of incoming air and the radiators.

An electric switch (not shown) can be placed exteriorly of the furnace, or the circuit 35 may be connected with suitable switch mechanism which in turn is controlled by a thermostat (not shown).

Manifestly, a draft is produced more readily by suction than by pressure, and it is 40 for this reason that the radiators are located in the upper part of the casing. Cold air entering through the inlet (10), contacts with the radiators which are heated by the resistance bars. It will be understood in 45 this connection that the plates carrying the resistance bars are heated first, and that the heat thus generated is radiated to the im- perforate plates. As the heat rises it strikes the deflector which absorbs and radiates it 50 in vertical and transverse planes and outwardly through the outlets (9) to registers (not shown) in various rooms of the house.

We have shown six radiator units, inclusive 55 of the water manifold, but it is obvious that this arrangement can be varied at will. The precise contour of the heat deflector, and other structural features, may also be altered without departing from the spirit and principle of our invention.

60 What we claim, is:—

1. A hot air furnace comprising a casing 65 provided with an inlet and an outlet, a plurality of spaced plates supported within said casing and extending longitudinally in the general direction of and

exposed to the flow of air through said casing, certain of said plates each having a longitudinal slot extending through the plate, an electrical resistance element mounted within each slot, and electrical connections for said elements. 70

2. A hot air furnace comprising a casing 75 provided with an inlet and an outlet, a plurality of plates radially supported within said casing, the alternate plates having slots, an electrical resistance element mounted within each slot, and electrical connections for said elements.

3. A hot air furnace comprising a casing 80 provided with an inlet and an outlet, a water manifold supported within said casing and also provided with a water inlet and a water outlet, said manifold having its side wall provided with a slot therein terminating short of the ends of the manifold, 85 an electrical resistance element mounted within and substantially free of the walls of said slot, and electrical connections for said element.

4. An electrically heated appliance 90 comprising a casing, a metal radiator plate having an elongated slot therein and mounted within said casing, an electrical resistance element of bar-shape having a smaller diameter than the width of said slot and being 95 mounted in said slot with the body portion of said resistance element free of the walls of said slot, and electrical connections for said resistance element.

5. An electrically heated appliance 100 comprising a casing, a single-piece water manifold mounted within said casing and having a water inlet and a water outlet, said manifold being provided with a lengthened slot 105 in the form of an aperture extending wholly through the material of opposed walls of said manifold, the ends of said slot being defined by hollow water-containing portions of said manifold, a longitudinally extending resistance element mounted in and 110 spaced from the walls of said slot, and electrical connections for said element.

6. An electrically heated air-heating furnace comprising a casing, a radiator plate arranged upright within said casing and having attachment lugs at opposite corners, and provided with a diagonal slot, an electrical resistance element mounted within said slot, and electrical connections for said element. 115

7. A hot air furnace comprising a casing 120 provided with an inlet and an outlet, an upright support, a heat deflector, a plurality of radiator plates secured vertically to and between said upright support and said deflector, electrical resistance elements carried by certain of said plates, and electrical connections for said elements.

8. An electrically heated appliance 125 comprising a casing, a radiator plate disposed

- within said casing and having a slot therein, an electric resistance element arranged medially of said slot, a clamp for opposite ends of said element, a bridge disposed 5 transversely of said slot, and a yieldable member between the clamp and the bridge.
9. A hot air furnace provided with an inlet and an outlet, a plurality of radiator plates arranged vertically adjacent the upper 10 portion of said casing, a support for the base of said plates, an inverted dome secured adjacent the top edges of said plates, and a concave top for the casing, said dome and said concave top serving conjunctively as a 15 heat deflector.
10. A hot air furnace comprising a casing provided with an inlet and an outlet, a plurality of radiator plates mounted in said casing, electrical resistance elements 20 carried by certain of said plates, a heat deflector, simulating in contour an inverted truncated cone, secured to the upper edges of said elements below the top of said casing.
- 25 11. A hot air furnace comprising a casing provided with an inlet and outlets, and a concave top between the outlets, a plurality of radiator plates mounted in said casing, electrical resistance elements carried by cer- 30 tain of said plates, a heat deflector, simu-
- lating in contour an inverted truncated cone, secured to the upper edges of said elements below the top of said casing, the said concave top and said deflector being spaced apart and occupying a relatively nested re- 35 lationship.
12. A hot air furnace comprising a casing provided with an inlet and outlets, and a concave top between the outlets, a plurality of plates radiating from the center of the 40 casing, electrical resistance elements carried by certain of said plates, a heat deflector, simulating in contour an inverted truncated cone secured to the upper edges of said elements below the top of said casing, the said concave top and said deflector being spaced apart and occupying a relatively nested re- 45 lationship.
13. A hot air furnace comprising a casing provided with an inlet and an outlet, a plurality of radiator plates arranged perpendicularly and extending substantially one- 50 half of the height of the casing, and means for electrically heating said plates.

Signed at Milwaukee, in the county of 55
Milwaukee and State of Wisconsin, this
14th day of September, 1923.
